UNITED STATES PATENT OFFICE

2,034,003

PRINTING MACHINE

Frederick Shurley, Los Angeles, Calif.

Application March 10, 1934, Serial No. 715,025

15 Claims. (Cl. 101—115)

The present invention relates to means for printing, illustrating and coating articles such as paper, cardboard, leather, celluloid, cellophane, glass, tin, metal, silk, cotton and other fabrics and materials. It has particular reference to a machine for spraying a covering coat of suitable color.

In order to provide paper and similar fabrics or materials with a plurality of coatings of any desired character it is necessary to use a printing, painting, spraying or like process to cover the surface. Such operations may be very expensive to carry out by means of machines as at present constructed or by hand on a large scale because of the handling required, the necessity for applying a coating evenly, of rotating the article, drying, etc.

The present invention provides a machine which is capable of performing various operations automatically. The machine is constructed to receive paper and similar fabrics or materials fed to it by any suitable mechanism, or manually, to hold the paper and similar fabrics or materials, to move the table over a prescribed opening wherein the coating is applied, to rotate the table, to manipulate the coating-applying means so that the paper and similar fabrics or materials are properly coated, to retain the paper and similar fabrics or materials, preferably until the coating is dried, then to release the paper and similar fabrics or materials for removal either by suitable mechanism or manually, thus forming a continuously operating machine capable of high production with a minimum of care and attention.

One object of the invention is the provision of a machine having a rotating table for receiving, holding and manipulating an article to be printed or coated.

Another object is the provision of such a rotating table provided with a plurality of openings or stations for a plurality of colors.

Another object of the invention is the provision of automatically operated holding and releasing means for the paper and similar fabrics or materials to be printed or coated.

A particular object of the invention is the provision of automatically controlled suction means for holding and releasing the paper and similar fabrics or materials.

Another object is the holding of steel plates or stencils on to the paper or similar fabrics or materials by means of magnetism to enable a clean and clear impression to be reproduced on the paper or similar fabrics or materials.

Still another object of the invention is the pro-

vision of a travelling coat-applying device capable of motion to cover any predetermined portion, or all of the surface, of the paper or similar fabrics or materials to be printed or coated.

Still another object of the invention is the provision of means to manipulate or revolve the paper or similar fabrics or materials for properly presenting its surface for application of the printing or coating.

Another object of the invention is the combination of some or all of the foregoing features into a single machine as defined in the appended claims.

In the accompanying drawings I have shown a machine which combines all of the various features above referred to and many other and ancillary features which contribute to the proper functioning of the machine. The machine of the drawings is given by way of example to explain the nature of the invention and it is not to be considered as a limitation of the invention to the particular machine described and illustrated. Although the machine of the drawings is specifically adapted to print or coat on paper or similar fabrics or materials, it is to be understood that modifications and changes are contemplated for other uses of the machine, as will appear from the scope of the appended claims.

Other objects, advantages, and features of invention may appear from the accompanying drawings, the subjoined detailed description, and the appended claims.

In the drawings

Figure 1 is a half plan view of my machine, the other half being broken away to show the structure below.

Figure 2 is a fragmentary, sectional view of the table top, taken on line 2—2 of Figure 1.

Figure 3 is a side elevation of my machine.

Figure 4 is a fragmentary, sectional view on the line 4—4 of Figure 1.

Figure 5 is a transverse sectional view of the spray gun actuating device.

Referring more particularly to the drawings, in general, the machine comprises a moving member 1, such as a rotating table or disc. A plurality of openings 2 are cut thru the table 1 and these openings are equidistantly spaced around the table, for a purpose to be further described. Around each opening 2, I provide a holding frame 3, the purpose of these frames is to securely clamp a stencil over each of the openings. The stencils being cut from a suitable metal. Each stencil has the peculiar pattern or configuration cut thereon which conforms to the

particular color which it is desired to apply therewith. All of which is usual and well known in the art.

The table 1 is rotatably mounted on a central pedestal 4, and the table is also tilttable, as will be further described. A spider 5 is secured to the table at the center thereof, and a pin 6 extends into the spider and is secured in a central dome 7. The pin 6 rests on a ball thrust bearing 8 so that the table can easily rotate. A pair of bearing hangers 9—9 extend upwardly from the pedestal 4, and a tilting frame 10 is journaled in the hangers 9. The pin 6 also extends into the tilting frame 10, thus securely centering the table 1.

An operating arm 11 extends from the tilting frame 10 and this frame is tilted in the following manner: A foot treadle 12 is pivotally mounted to the pedestal 4 adjacent the bottom thereof, and a rod 13 extends upwardly from the treadle 12 to a spring 14, which spring is secured or attached to the outer end of the arm 11. Thus it will be evident that when the treadle 12 is depressed by the foot of the operator, the entire table 1 will be tilted in the bearings 9—9 and the purpose of this tilting operation will be further described. When pressure is released from the treadle 12, it is necessary to return the table 1 to a horizontal position, and this is accomplished by a rubber belt 15 which extends over a post 16 which projects rearwardly from the tilting frame 10. A post 17 also projects from the pedestal 4 and the belt 15 encircles this latter post as well as the post 16. A stop block 18 rises from the top of the pedestal 4 and the post 16 is adapted to strike against this block thus holding the table 1 accurately in horizontal position. It is, of course, understood that the entire frame 10 and attached parts do not rotate. The table 1 moves in a rotary manner independent of this frame and upon the pin 6.

The table is held in tilted position by means of a catch bar 19 which is pivotally mounted to the pedestal 4 and engages an abutment 20 when the treadle 12 is depressed. A releasing link 21 is pivotally mounted in the treadle 12 and is adapted to engage the catch bar 19 when depressed by the foot of the operator. A supporting bracket 22 is secured to the pedestal 4 adjacent the top thereof, and this bracket projects forwardly.

Removably mounted on the outer end of the bracket 22 is an electro-magnet 23. This electro-magnet is constructed substantially as disclosed in my co-pending application for Electro-magnet for printing machines and the like, Serial Number 535,396. A trough or groove 24 is provided around the upper periphery of the magnet 23 for the purpose of transmitting the vacuum which is created in a pump 25. A hose, or hoses 26 extend from the vacuum pump 25 to the grooves 24 thus creating a partial vacuum which will securely and tautly hold paper, cloth, or other material to be acted upon over the top surface of the electro-magnet.

The vacuum pump 25 may be of any usual and well known design, and the detailed construction thereof forms no part of this invention.

As each of the openings 2 are brought into alignment with the electro-magnet 23, the table is then tilted by means of the treadle 12, as previously described, and the stencil which is held by the frame 3 is moved in juxtaposition to the material on the electro-magnet. When the table is tilted a contact is closed and current

is fed to the electro-magnet, thus energizing the same and the metal stencil is attracted and held closely upon the material to be worked upon. An arm 27 of the central spider 5, extends centrally of each of the openings 2, and these arms 5 are also radially arranged. The outer end of each arm is bifurcated as shown at 28, and the table 1 is provided with a hole 29 immediately below the bifurcation 28. An aligning pin 30 projects upwardly from a bracket 31 which is attached to the top of the pedestal 4. The aligning pin 30 extends upwardly thru the opening 29 and between the bifurcations 28 when the table top is tilted, thus the openings 2 are accurately positioned above the electro-magnet. A spring pressed plunger 32 bears against the bottom of the table 1 to act as a brake so that the table will not swing too freely.

As previously stated, the metal stencil is held by the magnet securely against the material to be printed or colored, and the paint or coloring material is then sprayed or otherwise carried thru the stencil and upon the surface of the paper, or the like.

In the present instance I prefer that the color shall be sprayed on thru a suitable gun which may be either automatically or hand operated. Trays 33 and 34 are provided, and the operator may place his various spray guns containing the different colors upon these trays while the table 30 is being manipulated. All that is necessary for the operator to do is to feed the paper on to the top of the electro-magnet where it is held by the vacuum from the pump 25.

The foot treadle 12 is then pressed which tilts 35 the table and the stencil is moved on to the paper. The tilting movement of the top closes the electrical circuit and the electro-magnet is energized so that the metal stencil is securely held on the paper. The color is then sprayed thru the stencil, the treadle 12 is subsequently released and the next stencil is moved into position. This process continues until all of the stencils required have been brought into position over the paper to be printed and have been sprayed thru. A 45 quick drying color coating may be used so that no time need be lost in waiting for the material to dry before the next stencil is placed in position.

It is to be understood that various changes in construction may be made in the machine for effecting the purposes of this machine, and for adapting it to articles and coatings of different natures as will be evident from the scope of the invention as defined in the appended claims.

In Figure 5, I have shown a device for quickly 55 oscillating the spray gun within a limited range over the stencil mounted in the table 1, as previously described. A fitting 35 is provided into which a spray gun of usual and well known design is mounted. A hose 36 extends to the fitting 35 so that air is fed to the spray gun in the usual and well known manner, or the hose may feed the liquid coating material along with the air to the gun.

A reciprocating carrier 37 in the form of a 65 ring structure is guided in its reciprocation upon a rod 38 which rod is secured in frame plates 39—39. The frame plates rise from a base 40 which may be suitably mounted adjacent to the table and in such a position that the spray gun 70 extends over the stencils. The carrier 37 has a depending bearing 41 which encircles the rod 38, thus guiding the carrier in its movement.

A cam cylinder 42 has a spiral groove 43 cut on the surface thereof, and a pin 44 depends from

the carrier 37 and extends into the groove, thus causing the carrier to reciprocate as the cam cylinder is rotated. A shaft 45 extends from the cam cylinder and is driven from a suitable source of power, not shown.

Having described my invention, I claim:

1. A printing machine comprising a table, means rotatably mounting said table, said table having a plurality of openings therein, stencil clamping means at said openings whereby a stencil is secured over said openings, material holding means, means tiltably mounting said table whereby the openings therein, with the stencil, are placed in juxtaposition to the material holding means, the color being adapted to be projected thru the stencil upon the material.

2. A printing machine comprising a table, means rotatably and tiltably mounting said table, said table having a plurality of openings therein, stencils adapted to fit over said openings, stencil clamping means, an electro-magnet below the table, and means on the electro-magnet whereby the material is smoothly held thereon.

3. A printing machine comprising a table, means rotatably and tiltably mounting said table, said table having a plurality of openings therein, stencils adapted to fit over said openings, stencil clamping means, an electro-magnet below the table, and means on the electro-magnet whereby the material is smoothly held thereon, and centering means whereby each opening in the table is accurately positioned over the electro-magnet.

4. A printing machine comprising a table, means rotatably and tiltably mounting said table, said table having a plurality of openings cut therein, stencils fitted over said openings, clamping means for said stencils, manual means to tilt said table, an electro-magnet under said table, and means on the electro-magnet to hold the material.

5. A printing machine comprising a table, means rotatably and tiltably mounting said table, said table having a plurality of openings cut therein, stencils fitted over said openings, clamping means for said stencils, manual means to tilt said table, an electro-magnet under said table, vacuum means on the magnet whereby the material is smoothly held thereon, and means centering the openings in the table over the magnet.

50 6. A printing machine comprising a table, means tiltably and rotatably mounting said table, said table having a plurality of openings cut therein, stencils adapted to fit over said openings, stencil clamping means, an electro-magnet under the table, said magnet having grooves formed around the periphery thereof, a vacuum pump, a tube extending from the pump to said grooves whereby a partial vacuum is maintained in the grooves, the material being adapted to be placed on the electro-magnet over the grooves and held by the vacuum, manual means to tilt said table whereby the stencil is pressed upon the electro-magnet and said stencil is attracted by the magnet and pressed upon the material.

65 7. A printing machine comprising a table, means tiltably and rotatably mounting said table, said table having a plurality of openings cut therein, stencils adapted to fit over said openings, stencil clamping means, an electro-magnet under the table, said magnet having grooves formed around the periphery thereof, a vacuum pump, a tube extending from the pump to said grooves whereby a partial vacuum is maintained in the grooves, the material being adapted to be placed on the electro-magnet over the grooves

and held by the vacuum, manual means to tilt said table whereby the stencil is pressed upon the electro-magnet and said stencil is attracted by the magnet and centered means whereby the openings in the table are accurately positioned over the magnet.

8. A printing machine comprising a table, a pivot pin in the center of the table, a tilting frame, said pin being journaled in the tilting frame, a pedestal, said tilting frame being journaled on top of the pedestal, said table having a plurality of openings cut therein, metal stencils mounted over said openings, clamping means for said stencils, a foot treadle, a link extending from the foot treadle to the tilting frame whereby said frame and table are tilted, an electro-magnet below said table, means on the electro-magnet adapted to hold the material, said openings in the table being moved into alignment with the electro-magnet whereby the stencils are superposed upon the magnet when the table is tilted.

9. A printing machine comprising a table, a pivot pin in the center of the table, a tilting frame, said pin being journaled in the tilting frame, a pedestal, said tilting frame being journaled on top of the pedestal, said table having a plurality of openings cut therein, metal stencils mounted over said openings, clamping means for said stencils, a foot treadle, a link extending from the foot treadle to the tilting frame whereby said frame and table are tilted, an electro-magnet below said table, said magnet having grooves around the periphery thereof, a vacuum pump, a tube extending from the vacuum pump to the grooves whereby a partial vacuum is maintained in said tube thereby holding the material on the magnet, said stencils being superposed upon the electro-magnet when the table is tilted.

10. A printing machine comprising a table, a pivot pin in the center of the table, a tilting frame, said pin being journaled in the tilting frame, a pedestal, said tilting frame being journaled on top of the pedestal, said table having a plurality of openings cut therein, metal stencils mounted over said openings, clamping means for said stencils, a foot treadle, a link extending from the foot treadle to the tilting frame whereby said frame and table are tilted, an electro-magnet below said table, said magnet having grooves around the periphery thereof, a vacuum pump, a tube extending from the vacuum pump to the grooves whereby a partial vacuum is maintained in said tube thereby holding the material on the magnet, said stencils being superposed upon the electro-magnet when the table is tilted, and aligning means whereby said openings are accurately positioned above the electro-magnet.

11. A printing machine comprising a table, a pivot pin in the center of the table, a tilting frame, said pin being journaled in the tilting frame, a pedestal, said tilting frame being journaled on top of the pedestal, said table having a plurality of openings cut therein, metal stencils mounted over said openings, clamping means for said stencils, a foot treadle, a link extending from the foot treadle to the tilting frame whereby said frame and table are tilted, an electro-magnet below said table, means on the electro-magnet adapted to hold the material, said openings in the table being moved into alignment with the electro-magnet whereby the stencils are superposed upon the magnet when the table is tilted, an aligning pin below the table, said table having holes cut therein adjacent each of said open-

ings thru which the aligning pin projects to accurately position said openings over the electro-magnet.

12. A printing machine comprising a table, a pivot pin in the center of the table, a tilting frame, said pin being journaled in the tilting frame, a pedestal, said tilting frame being journaled on top of the pedestal, said table having a plurality of openings cut therein, metal stencils mounted over said openings, clamping means for said stencils, a foot treadle, a link extending from the foot treadle to the tilting frame whereby said frame and table are tilted, an electro-magnet below said table, said magnet having grooves around the periphery thereof, a vacuum pump, a tube extending from the vacuum pump to the grooves whereby a partial vacuum is maintained in said tube thereby holding the material on the magnet, said stencils being superposed upon the electro-magnet when the table is tilted, an aligning pin below the table, said table having holes cut therein adjacent each of said openings thru which the aligning pin projects to accurately position said openings over the electro-magnet.
13. A printing machine comprising a table, means rotatably mounting said table, stencil holding means on said table, material holding means, said stencil holding means being adapted to be positioned in juxtaposition to the material holding means whereby the color may be projected thru the stencil holding means upon the material, thereby impressing the outline of a

stencil upon the material, color spraying means, and means reciprocally mounting said color spraying means adjacent the stencil.

14. A printing machine comprising a table, means rotatably and tiltably mounting said table, 5 said table having a plurality of openings therein, stencils adapted to fit over said openings, stencil clamping means, an electro-magnet below the table, and means on the electro-magnet whereby the material is smoothly held thereon, color 10 spraying means, and means reciprocally mounting said color spraying means adjacent the stencil.

15. A printing machine comprising a table, means tiltably and rotatably mounting said table, 15 said table having a plurality of openings cut therein, stencils adapted to fit over said openings, stencil clamping means, an electro-magnet under the table, said magnet having grooves formed around the periphery thereof, a vacuum pump, a 20 tube extending from the pump to said grooves whereby a partial vacuum is maintained in the grooves, the material being adapted to be placed on the electro-magnet over the grooves and held by the vacuum, manual means to tilt said table 25 whereby the stencil is pressed upon the electro-magnet and said stencil is attracted by the magnet and pressed upon the material, color spraying means and means reciprocally mounting said color spraying means adjacent the stencil. 30

FREDERICK SHURLEY.
